RECEPTACLE FOR RODENT POISON

James D. Reifsnyder, Flushing, and Sixten I. Johnson, College Point, N. Y., assignors to Lily-Tulip Cup Corporation, New York, N. Y., a corporation of Delaware

Application April 14, 1949, Serial No. 1,990

Term of patent 14 years

(Cl. D31—4)

To all whom it may concern:

Be it known that we, James D. Reifsnyder, a citizen of the United States and a resident of Flushing, New York, in the county of Queens and State of New York, and Sixten I. Johnson, a citizen of the United States and a resident of College Point, New York, in the county of Queens and State of New York, have invented a new, original, and ornamental Design for a Receptacle for Rodent Poison, of which the following is a specification, reference being had to the accompanying drawing, forming a part thereof, where-in:

Fig. 1 is somewhat enlarged bottom plan view of a receptacle for rodent poison embodying our new design;

Fig. 2 is a side elevational view, partly in section, and

Fig. 3 is a top plan view thereof.

We claim:

The ornamental design for a receptacle for rodent poison, substantially as shown.

JAMES D. REIFSYNDER.
SIXTEN I. JOHNSON.
